UNITED STATES PATENT OFFICE.

AUSTIN F. JACKSON, OF TAUNTON, MASSACHUSETTS, ASSIGNOR TO REED AND BARTON CORPORATION, OF TAUNTON, MASSACHUSETTS.

DESIGN FOR A BORDER OR MOUNT FOR SILVERWARE.

SPECIFICATION forming part of Design No. 36,153, dated December 9, 1902.

Application filed August 18, 1902. Serial No. 120,070. Term of patent 14 years.

To all whom it may concern:

Be it known that I, AUSTIN F. JACKSON, a citizen of the United States, residing at Taunton, in the county of Bristol and State of Massachusetts, have invented and produced a new, original, and ornamental Design for the Border or Mount for Silverware, of which the following is a specification, reference being had to the accompanying drawing, forming a part thereof, in which an elevation is shown of the said border or mount.

As shown in the drawing, the mount consists of two ornamental forms or pieces connected by a graceful bar.

15 This design may be repeated several times on any piece of tableware to form the complete mount.

The leading or material feature of my design consists in the mount or border having spaced ornamental decorations connected by 20 a substantially plain portion, as shown.

What I claim as new, and desire to secure by Letters Patent, is—

The ornamental design for a border or mount for silverware, or similar article, substantially as shown and described.

In testimony whereof I have signed my name to this specification, in the presence of two subscribing witnesses, on this 29th day of July, A. D. 1902.

AUSTIN F. JACKSON.

Witnesses:

GEORGE E. CHAMBERS,
HERBERT O. WOOLLEY.
